UNITED STATES PATENT OFFICE.

HERBERT K. PORTER AND ORSON K. PORTER, OF EARLY, OREGON.

MATCH-SAFE.

No. 913,978.

Specification of Letters Patent.

Patented March 2, 1909.

Application filed September 27, 1906. Serial No. 336,502.

To all whom it may concern:

Be it known that we, HERBERT K. PORTER and ORSON K. PORTER, citizens of the United States, residing at Early, in the county of 5 Sherman, State of Oregon, have invented certain new and useful Improvements in Match-Safes; and we do hereby declare the following to be a full, clear, and exact description of the invention, such as will enable 10 others skilled in the art to which it appertains to make and use the same.

This invention has relation to that class of mechanically operated match boxes or holders that are designed by their operation to 15 deliver but one match at a time.

The invention, in its nature, comprises an outer casing adapted to support the trunnions of a rotary cylinder that is operated intermittently, and is provided with a series 20 of match-receiving chambers, each having means to catch a match as the cylinder is rotated, and a hinged lid to each chamber that is opened as the cylinder is rotated to release or drop the aforesaid match.

25 The nature of the invention is fully ascertainable from the annexed drawings, forming a part of this specification, in view of which it will first be described with respect to its construction and mode of operation, 30 and then be pointed out in the subjoined claims.

Of the said drawings—Figure 1 is a side elevation. Fig. 2 is a plan. Fig. 3 is a vertical sectional view in the plane 3—3 of Fig. 2. 35 Fig. 4 is a sectional view in the plane 4—4 of Fig. 2. Fig. 5 is a sectional view in the plane 5—5 of Fig. 2. Fig. 6 is a perspective detail of one of the lids. Fig. 7 is a bottom view of the tray post.

40 Similar figures of reference designate similar parts or features, as the case may be wherever they occur.

In the drawings 10 designates a base, and 45 11 a casing suitable to support a rotary drum, 12, and its operating means.

The drum comprising the recessed hub 12', the sides 12, and the cylindrical chambered casing 14 is provided with a plurality of chambers 13, in its outside extending from 50 side to side, for the receipt of matches, which chambers are closed by a lid, 15, hinged at one edge to the cover, the said lids being substantially semi-cylindrical in cross section, as shown, the outside of 55 the drum with which the curved lid comes into contact, being correspondingly shaped.

Within each chamber 13, is a lip 16, of a width just wide enough to hold a single match, as shown in Fig. 3. Near each end of the lip 16 there is a notch 17, formed in the free edge of the cover for the head of the match caught by the lip, 16, to fall into. The cover 15 on the end adjacent to the side 18 of the casing is offset or extended, as at 19, for a purpose to be presently explained. 60 65

The end of the drum opposite to that facing the side 18 of the casing is provided with a ratchet disk, 20, the teeth of which are engaged by the ends of the spring-pressed pawls, 21, connected with a lever, 70 22, in such manner that both will operate to turn the drum 12 in the direction indicated by the flight of the arrow marked thereon, one pawl operating on the ratchet wheel as the lever is depressed and the other as it is 75 raised. But one pawl may be used if the construction is so contrived that it will rotate the cylinder to the necessary extent that is, the distance taken up by one chamber 13 and one of its walls in the drum. This fact 80 will appear obvious, and it will also be plain that the use of two pawls to move the ratchet wheel, as shown and described, is to limit the movement of the pawl-actuating lever to a short distance and to act as a 85 check on the drum and keep it moving in the desired direction.

The manually operated lever 22 is acted upon by a spring 23, connected with the casing and bearing on the under side of the lever 90 to raise it. The lever is secured to the casing in that its rear end is bent at a right angle to its main portion, as at 25, and is projected through round notches, 26 formed in the rear sides of cleats 27 secured to the inside of 95 the back of the casing, the extreme portion of the rearward part of the lever being bent at a right angle and inclined downward so that its lower end may engage an angular bend, 28, formed in a spring wire 29, the vertical portion of which extends up along-side of the rear part of the side casing 18, and is fastened at its upper end thereto and furthermore has pegs or tacks on its opposite side to give it proper tension, the horizontal portion 100 105 30 of the said wire, 29 extending forward and having an upturned end 31, that projects into the bottom of the post 32 upon the top of which there is a match-receiving tray 33, roughened or otherwise provided on its upper surface to keep the matches from rolling off. The post 32 has a hole 34 formed ver- 110

tically in its lower end into which extends a pin 35 to adapt the post to turn on the said pin and move the receiving tray 33 toward the cylinder 12 to receive the match that 5 may be delivered therefrom and then to move back into normal position away from the cylinder.

The construction and arrangement of the lever, its connections, and the wire 29 and its 10 connections is such that when the lever is operated to effect the delivery of a match, as will be presently described, the down-turned end of the lever, will engage the bend 28 of the spring wire 29 and draw the horizontal 15 portion 30 forward, and pull upon the post 32, with which the upturned end 31 is eccentrically connected, and turn said post so as to move the tray, 33 inward toward the cylinder. When the lever is released the resiliency 20 of the wire 29, will operate to turn the post and tray back to first position.

On the inside of the end 18 of the casing there is secured an inwardly projecting rim 36 formed from sheet metal and being circular in form so far as it extends. At the top 25 the circular rim is open, and at the forward end of the open part there is a short curved flange 37, formed in a manner similar to the rim 36 set inward slightly from the said end. The construction and arrangement of the 30 said rim and flange and their relationship to the drum and its parts is such that as the drum rotates between the open ends of the circular rim the latter will act upon the outer 35 side ends of the hinged lids 15, to keep them closed, but when an offset or projection 19 on one end of the lid reaches the flange 37 the latter will engage the said projection and by reason of its form raise the lid, and let drop 40 the match that may have been caught on the lip 16 (which is only wide enough to hold one) upon the tray which will have been turned to position to receive it, as has already been explained. As the cylinder is further rotated 45 the projection 19 on the end of the lid will pass the flange 37 and close by gravity until it engages the rim 36, which will hold it closed, as before set forth.

The outside surface of the covers and lids, 50 will be left smooth or in other conditions to receive advertisements thereon, which will be brought successively into view as the drum is rotated.

It will be understood that the chambers 13 55 will have matches placed in them with their heads facing the side 18 so that the said heads will fall into the notches 17, of the lids when on the lip 13. Of course the notch 17 may be made in the edge of the lid at the 60 other end and the position of the matches in the chambers 13 be reversed without changing the functions of the device or notches can be made at both ends. The said notches also serve as means for inserting the end of a 65 match therein to open the lid.

It is recognized that other changes and variations may be made in the form and arrangement of parts and features of a device embodying the invention without departing from its general nature or spirit, for example, 70 it is clear that the outside of the drum need not have the precise conformation shown.

What is claimed, is:—

1. A mechanically operated match - box comprising a casing, a rotary drum provided 75 with a plurality of match receiving chambers each having an access opening, a hinged lid closing the access-opening to each chamber, means for supporting a single match at the opening edge of the lid, means for rotating the drum intermittently, and means for raising said lids at a predetermined place, to deliver a match.

2. A mechanically - operated match box comprising a casing, a rotary drum provided 85 with a plurality of match receiving chambers each having an access opening, a hinged lid closing the access opening to each chamber, means for supporting a single match at the opening edge of each lid, means for rotating 90 the drum intermittently, and means for raising the lids at a predetermined place, to deliver said match, combined with means for closing the lids and keeping them closed 95 until opened as stated.

3. A mechanically - operated match - box comprising a casing, a rotary drum provided with a plurality of match receiving chambers each having an access opening, a hinged lid closing the access-opening to each chamber, means for supporting a single match at the opening edge of the said lid, means for rotating the drum intermittently, and means for raising said lids at a predetermined place 100 to deliver said match, combined with a tray to receive the match delivered, and means for actuating the said tray.

4. A mechanically operated match - box comprising a casing, a rotary drum provided 105 with chambers for the reception of matches, each chamber having an access opening, a hinged lid closing the access opening to each chamber, the free edge of each lid being provided with a lip extending over the upper edge of the outer wall of the chamber with 110 which it co-operates.

5. A mechanically operated match - box comprising a casing, a rotary drum provided with chambers for the reception of matches, each chamber having an access opening, a hinged lid closing the access opening to each chamber, the free edge of each lid being provided with a lip extending over the upper edge of the outer wall of the chamber with 115 which it co-operates, and a notch in the edge of the cover for the head of the match, combined with means for periodically lifting the cover to deliver the match on the lip.

6. A mechanically operated match - box comprising a casing, a rotary drum provided 120

with chambers for the reception of matches, each chamber having an access opening to each chamber, the free edge of each end being provided with a lip extending over the upper edge of the outer wall of the chamber with which it coöperates, combined with means for periodically lifting the lid to deliver a match and closing the lid and holding it closed as stated.

10 7. The combination, with the casing provided with a circular rib and flange, of a rotary drum supported in the casing and having match - receiving chambers, each chamber having an access opening, a hinged

lid for each chamber to control the said 15 openings, each of the said lids being provided on one end with an offset to be engaged by the said flange to temporarily open the lid, the rim engaging the lid to close it and keep it closed for a major part of the 20 time.

In testimony whereof, we affix our signatures, in presence of two witnesses.
